UNITED STATES PATENT OFFICE

LOUIS BERMANN, OF MELROSE PARK, ILLINOIS, ASSIGNOR TO ELECTRICAL ENGINEERS EQUIPMENT CO., OF MELROSE PARK, ILLINOIS, A CORPORATION OF ILLINOIS

POTENTIOMETER RESISTANCE

Application filed May 19, 1930. Serial No. 459,630.

This invention relates to potentiometers, more particularly to wire wound potentiometers, either low or high resistance and of suitable current carrying capacity.

5 In the control of the volume of radio sets, in television equipment, in X-ray equipment, in photometric work and in other scientific measurement work, potentiometers are generally employed. It is essential in such 10 cases to have a straight line stepless resistance unit of reasonable size.

In the prior Patent No. 1,680,744, issued to Alfred F. C. Lotz, August 14, 1928, is disclosed a rheostat consisting of two drums or 15 cylinders having threaded external surfaces and disposed with their axes substantially parallel. A resistance wire is wound from one drum to the other to vary the resistance of the external circuit, in a manner which 20 will be best understood from a perusal of this patent.

In my present invention, I alter the design of a rheostat of this same general class to 25 make it into a potentiometer, the alterations consisting principally in providing a third contacting element located substantially midway between the two drums and over which the wire of the resistance unit is passed as it 30 is unwound from one drum and wound onto the other. Both drums are composed of an insulating material and electrical connections to the unit are made in such a manner that the entire length of the resistance wire 35 is always in one of the electrical circuits through the unit. The position of the auxiliary contact arm relative to the ends of the wire alters the resistance between that arm and the ends of the wire, thereby securing the 40 resistance variation commonly secured in so-called potentiometers.

Other advantages of my invention not specifically mentioned here will be apparent from a reading of the detailed description and claims which follow.

45 Now, in order to acquaint those skilled in the art with the construction and operation of a device embodying my present invention, I shall describe in connection with the accompanying drawing a particular embodiment of 50 the invention.

In the drawing:—

Figure 1 is a bottom view taken on the line 1—1 of Figure 3 and showing the terminals of the potentiometer;

Figure 2 is a top view taken on the line 2—2 of Figure 3 and showing the operating knob;

Figure 3 is a cross sectional view taken along the line 3—3 of Figure 2, looking in the direction of the arrows;

Figure 4 is a cross sectional view taken along the line 4—4 of Figure 2, looking in the direction of the arrows;

Figure 5 is a cross sectional view taken along the line 5—5 of Figure 3, looking in the direction of the arrows; and

Figure 6 is a cross sectional view taken along the line 6—6 of Figure 3, looking in the direction of the arrows.

To illustrate the relative dimensions of a commercially practical embodiment of my invention, the device shown in the accompanying drawing a substantially full size of that device. This is merely illustrative and is in no wise intended to limit the size or proportions of the invention.

Referring to the drawing, the device is enclosed within an oblong case having the end walls consisting of front wall 5 and back wall 6, which may be of any suitable insulating material. The back 6 is shown in the form of a detachable cover. The walls 5 and 6 may be oblong, with their ends rounded or semi-circular, each end 5 and 6 having a marginal flange 7.

A cover or case 10, which may comprise a relatively thin sheet or strip of transparent material, for example, celluloid or isinglass material, such as "Pyralin", is folded to conform or fit within the flange 7 and with its opposite or free ends meeting or overlapping. The opposite edges of the cover 10 fit within the flanges 7, so that the cover is held firmly and properly in place by the means which holds the end walls 5 and 6 together.

Rotatably mounted within the cover 10 and between the end walls 5 and 6 with their axes substantially parallel are insulating cylinders or drums 12 and 13.

The cylinder 12 may be formed of insulating material, such as a phenol condensation

product, and it comprises an axially bored hub 14 and a surrounding cylindrical wall 15 having an open end and a closed end 17. Integral webs 18 may be provided between the hub 14 and the wall 15. The cylinder 12 is rotatably journaled upon a shaft 19, the opposite ends of which are reduced to provide shoulders which abut and space the end walls 5 and 6. The reduced ends of the shaft 19 are threaded and these threaded ends extend through openings in the end walls 5 and 6 and engage in nuts 20, which, when tightened or brought up, clamp the end walls 5 and 6 firmly together. Suitable washers may be interposed between the end walls 5 and 6 and the nuts 20, as shown. The cylinder 12 is thus mounted to rotate on the shaft 19, and the shaft 19 is rigidly secured in the case and spaces and joins the end walls thereof.

20 The cylinder 13 is preferably also formed of insulating material, such as a phenol-condensation product, and it comprises an axially bored hub 24 and a surrounding cylindrical or annular wall 25 having an open end 26 and a closed end 27. The wall 25 is provided internally with a longitudinally extending integral lug or shoulder 28, and the hub 24 terminates short of the open end of the cylinder 13. The cylinder 13 is rotatably journaled upon a shaft 29, the opposite ends of which are reduced to form shoulders which abut and space the end walls 5 and 6 symmetrically upon opposite sides of the driving shaft 30. As with the shaft 19, the reduced ends of the shaft 29 are threaded and these threaded ends extend through openings in the end walls 5 and 6 and engage in nuts 32 which clamp the end walls 5 and 6 firmly together. As before, suitable washers are preferably interposed between the ends 5 and 6 and the nuts 32. The cylinder 13 is thus mounted to rotate on the shaft 29, which shaft 29 is rigidly secured in the case, and with the shaft 19 provides a symmetrical spacing and joining of the ends 5 and 6.

The closed end 17 of the cylinder or drum 12 has an annular recess 35 in which is secured a metallic annular contact or commutator ring 36, which ring is preferably composed of brass or other noncorrosive metal. The closed end 27 of the cylinder or drum 13 is also provided with an annular recess 27' in which is secured a metallic annular contact or commutator ring 36' of the same metal as the ring 36.

60 The resistance element comprises a strand or strands of resistance wire 37, preferably an alloy of nickel, or the like. One end of this wire or conductor 37 is wrapped on the drum 12 with its adjacent end turned in through a slot or recess 38, and is welded, soldered or otherwise connected electrically and mechanically to the ring 36 at 39.

65 The opposite end of the conductor 37 is wrapped upon the cylinder 13 with its end

turned in through a radial opening 40 and extended downwardly at 42 along the inside edge of the wall 25 and is welded, soldered or otherwise connected electrically and mechanically to the ring 36' at 37'. The external surface or periphery of the insulating cylinder 12 is threaded or grooved spirally at 43 to accommodate the turns of the wire 37, and to space and insulate them from each other. The external surface or periphery of the insulating cylinder 13 is similarly threaded or grooved spirally at 44 in the same direction, so as to accurately arrange the turns of the wire 37 thereon, and to guide the wire properly to and from the cylinder 12.

At one end the wire 37 preferably has a dead turn or two on the drum 12, that is, a turn or two which remains on the drum in the complete unwrapped position of the drum, and at its opposite end the wire 37 preferably has a similar dead turn or two on the drum 13. This provides belt friction between the respective drums and the opposite ends of the conductor 37 and relieves the joints or connections of the terminals of the wire 37 with the rings 36 and 36', respectively, of any stresses at the limits of rotation of the drums.

The opposite ends of the wire 37 have terminals or circuit connections for connecting the device serially or otherwise in the desired circuit. These connections comprise spring contact or brush arms 48 and 50. One of these arms is secured to the end wall 6 by a screw 52 which extends through and engages in a nut 53 which, with an additional nut 54, provides a binding post to which the desired circuit conductor may be conveniently connected mechanically and electrically. The mounting of the other contact arm upon the end wall 6 and its circuit connection are substantially the same. Spring washers 55 are preferably interposed between the end 6 and the nuts 53 to keep the contact arms tightly clamped to the back or cover 6.

110 The contacting ends of the arms 48 and 50, which have wiping contact on the rings 36 and 36', respectively, are preferably split or divided longitudinally at 58 to form spring ends for good, firm and maximum contact with the rings 36 and 36' at all times.

115 The contact arms 48 and 50 are mounted with their lengths extending longitudinally of the back 6 and preferably with one disposed on each side of the driving shaft 30. This provides a compact and symmetrical arrangement. The arms 48 and 50 are carried by the back 6 and removed and assembled therewith.

120 The arms are preferably prevented from rotating about their screws by boss or shoulder or in any other preferred manner.

125 For the purpose of firmly securing the rings 36 and 36' in the recesses 35 and 37', I tin the washers or rings 36 and 36', or coat them with

a suitable relatively soft conducting coating. The washers may be of brass, for example, and may be pressed into the recesses in the ends of the drums 12 and 13. This tinning or coating provides firm adhesion of the washers to the insulating drums 12 and 13, and it provides soft contact surfaces, which, upon operation of the device, I find are quickly grooved by the contact arms 48 or 50, this grooving of the arms thereinto forming good, maximum contact at all times. Subsequent hand tinning for connection of the wire 37 to the rings is also thereby avoided.

The driving shaft 30 extends between the cylinders or drums 12 and 13, which makes for compactness and symmetry. The inner or back end of the shaft 30 is reduced at 65 and this reduced end is rotatably journaled in the back cover wall 6. The forward part 20 of the shaft 30 is enlarged at 66 and the enlarged shaft part 66 is rotatably journaled in a bearing bushing or sleeve 68. The bushing 68 comprises an externally threaded cylindrical sleeve or thimble having an enlarged non-circular head 70 of square or other polygonal 25 formation, for example, which may be formed integral with the bushing sleeve. The inside surface of the wall 5 has a non-circular recess 72 conforming to the head 70 and adapted 30 to receive or accommodate same, the engagement of the head 70 in this recess 72 holding the bushing rigidly against turning in the wall 5 and limiting its forward or outward movement therethrough. A nut 73, threaded 35 externally upon the bushing 68 and against the wall 5, binds the bushing rigidly in said wall.

An additional nut 76 is provided on the threaded bushing 68 to thereby permit mounting of the unit upon a suitable panel in the customary single hole mounting method. The outer end of the shaft 30 has an operating knob 78 for turning the shaft. This knob 78 may be of insulating material with 45 a grooved or knurled periphery and a metal insert or sleeve 79 secured axially in the hub portion of the knob. The insert 79 is threaded to accommodate a radial screw 81 which threads through the sleeve 79 and into engagement with the shaft 30 to secure the knob rigidly thereon.

Between the front cover or end wall 5 and the forward end of the cylinders or drums 12 and 13, the driving shaft 30 has secured thereto a driving gear or pinion 82. Preferably, this pinion 82 is floated on the shaft 30 in the manner described in detail in the Lotz Patent No. 1,680,744, issued August 14, 1928, although other suitable means of attachment may be substituted therefor.

The driving pinion 82 is disposed between and meshes with a pair of gears 86 and 87, one for each of the cylinders or drums 12 and 13, the particular gear ratio shown being substantially two to one, the drums per-

forming one revolution for each two revolutions of the gear 82 or main shaft 30. The gear 86 may be formed by cutting the teeth directly in the end of the cylindrical insulating wall 15 of the drum 12, which makes a 70 rigid integral unit in which attachment means or connections between the gear and drums are eliminated.

As shown in Patent No. 1,680,744, the gear 87 has an axially bored hub loosely rotatable on the shaft 29, and projecting from the inner surface of the gear is a driving lug 89 which is preferably formed integral with the gear. Disposed within the cylinder 15 and coiled about the hub 24 is a helical tension spring 90. One end of this spring is turned out at 91 into engagement with the lug 28 formed integral with the closed end 27 of the drum 13. The opposite end is turned out at 92 for engagement or co-operation with the lug 89, providing a yieldable or take-up connection between the drum 13 and the gear 87, for maintaining the resistance wire 37 always properly tensioned or tightened.

The main shaft 30 is threaded as at 95 and if desired a rider 96 may be threaded thereon to limit the rotation of the knob 78 to thereby prevent tearing the wire 37 loose from the drums 12 and 13. The operation of this rider is more fully brought out in prior Patent No. 1,680,744. In the present invention the rider does not disengage the contact springs from the plates 36 and 36' to open the circuit when it is in its innermost position, but rather merely wedges against the back wall 6 or the pinion 82, to prevent further rotation of the shaft.

The potentiometer is used in an electrical circuit in which the contact arms 50 and 48 are connected to fixed points in the circuit through wires extended to the binding post 52, these connections being permanently and alterably made. The third or auxiliary contact of the potentiometer comprises a binding post 100 permanently connected to a metallic plate or bar 101 which engages the wire 37 midway between the drums 12 and 13. When the potentiometer is turned so that all the wire is wrapped on the drum 12, for example, the resistance between the binding post 100 and the left hand binding post 52, Figure 3, will be the resistance of that wire which permanently remains upon the drum 13. As the knob 78 is turned to unwrap the wire from the drum 12 and wrap it onto the drum 13, the resistance between these two binding posts increases as the amount of wire on the drum 37 increases. Conversely when all of the wire is on the drum 12, the resistance between the terminal 100 and the right hand terminal 52, Figure 3, is at its maximum, and that value of resistance is decreased as the knob is turned to unwrap the wire therefrom and to wind it on the drum 13.

The contacting plate 101 is preferably of rectangular cross section, and composed of a spring like material such as spring brass, spring bronze, or other suitable metal, and is tensioned to exert a pressure outward on the wire 37 so that that wire is always in good electrical contact with the strip 101. The movement of the wire across the surface of the strip 101 tends to wipe any dust or corrosion that may accumulate on the strip off of it, so that a good electrical contact between the wire and strip is thereby assured. The surface of the wire is likewise kept clean, so that in the operation of the potentiometer 15 the resistance value between the central terminal 100 and end terminal 52 can be changed noiselessly at all times.

Thus it will be seen that by suitable choice of the size and composition of the wire 37 20 the potentiometer may be made to any prescribed value of resistance, the unit so constructed being compact and sturdily built. The operation is simple and a wide range of resistance variation can be obtained through 25 the instrument.

While I have chosen to show a preferred embodiment of my invention, I have done so by way of example only, as there are many modifications which can be made by one skilled in the art without departing from the 30 teachings of my invention. I am therefore to be limited only by the scope of the appended claims.

What is claimed is:

- 35 1. In a potentiometer, a pair of cylindrical drums disposed with their axes parallel, a resistance wire wound on said drums and extending therebetween, one end of said wire being rigidly attached to each of said drums, means for making an electrical connection to each end of said wire, means for rotating said drums simultaneously to wind said wire from one to the other, and resilient, yielding stationary means for contacting with said wire as it passes from one drum to the other.
- 40 2. In a potentiometer, a pair of cylindrical drums disposed with their axes parallel, a resistance wire wound on said drums and extending therebetween, one end of said wire being rigidly attached to each of the drums, means for making an electrical connection to
- 45

each end of said wire, means for rotating said drums simultaneously to wind said wire from one to the other, and means consisting of a stationary, resilient, yielding bar between said drums for contacting said wire as it passes from one drum to the other. 70

3. In a potentiometer, a pair of cylindrical insulating drums disposed with their axes parallel, a resistance wire wound on said drums and extending therebetween, one end of said wire being rigidly attached to each of said drums, means including a plate attached to the drum and a stationary finger engaging said plate for making an electrical connection to each end of said wire, means 75 for rotating said drums simultaneously to wind said wire from one to the other, and stationary, resilient, yielding means for contacting with said wire intermediately of its ends as it passes from one drum to the other. 80

4. In a potentiometer, a pair of insulating plates, flanges on said plates, a pair of shouleder shafts disposed between said plates and holding them together with said flanges adjacent, a housing member disposed between 90 said plates and held in place by said flanges, a pair of insulating drums one mounted on each of said shafts, a resistance wire having an end attached to each of said drums and extending therebetween, stationary contacting means mounted on one of said plates and engaging a cooperating means on said drum to establish electrical connections with the ends of said wire, means on the opposite side of said plate for establishing an electrical 100 connection with said connecting means, a third stationary, resilient, yielding connecting means mounted on said plate and engaging said wire between said drum intermediately of its ends, means on the opposite side 105 of said plate for establishing an electrical connection with said third contacting member, and means mounted on the other plate for simultaneously rotating said drums to wind said wire on one of them while un-winding it from the other, to thereby vary 110 the resistance between said third contacting means and said pair of contacting means.

In witness whereof, I hereunto subscribe my name this 12 day of May, 1930.

LOUIS BERMANN.
